UNITED STATES PATENT OFFICE.

EUGENE G. SMITH, OF CHICAGO, ILLINOIS, ASSIGNOR OF ONE PER CENT TO GLENN S. NOBLE, OF CHICAGO, ILLINOIS; FRANK Z. SMITH, HARRY T. SMITH, AND MITTIE M. SLAGLE EXECUTORS OF SAID EUGENE G. SMITH, DECEASED.

MECHANICAL MOVEMENT.

Application filed September 26, 1921. Serial No. 503,276.

This invention relates to devices or transmissions, which are particularly adapted for use on railway cars for driving generators from the axles. Such generators are ordinarily mounted in substantially fixed positions on the bottoms of the car bodies while the axles are adapted to swing on the king-bolts. For this reason, it has been found difficult to provide a satisfactory drive or transmission from the axle to the generator. It will be noted that when the car passes around a curve, the axle will be thrown out of parallelism with the shaft of the generator, and if an ordinary belt and pulleys are used, the belt is very apt to be thrown off from the pulleys. In accordance with the present invention, I provide a pulley drive which is self adjusting, and provide means whereby the pulleys may be mounted so that they may remain in substantially the same vertical plane even if the car is passing around a curve, and consequently the entire transmission will be maintained in proper driving relation to the different parts.

The objects of this invention are to provide an improved axle transmission for railway cars; to provide a novel method of mounting and supporting a universally mounted pulley or driving member; to provide a guide for a universally mounted wheel; and in general to provide such an improved construction as will be described more fully hereinafter.

In the accompanying drawings illustrating this invention:

Figure 1 is a side view;

Figure 2 is a sectional view of the driving pulley;

Figures 3 and 4 are details of the driving pulley hub;

Figure 5 is a perspective view of one of the driving keys;

Figure 6 is a fragmentary cross sectional view of the railway truck;

Figure 7 is a plan view of the parts shown in Figure 6;

Figure 8 is a front view showing a por-

tion of the generator and its driving pulley; Figure 9 is a view similar to Figure 8, 50 but showing a modified form of guide for the driving pulley; and,

Figure 10 is an enlarged view of the generator pulley.

In the particular form of the invention shown in these drawings, the car truck 11 is provided with wheels 12 and axles 13, these parts being intended to represent any ordinary or standard form of car construction. The driving pulley 14 is mounted on 55 the axle 13, but as these axles vary more or less in diameter, I provide a novel arrangement for securing the same to the axle. A corrugated bushing 15 is placed around the axle and held by means of a band 16 at 60 one end thereof. The pulley 14 has a split hub 17 which is then placed over the bushing and held by means of bolts 18, which pass through holes 19 in the flanges of the hub. Keys 20 are then inserted between 65 the bushing 15 and the hub, the latter being provided with keyways 21, which terminate in radial slots 22 for receiving the head of the keys. After the keys have been inserted, a second band 23 is placed around 70 the projecting portion of the bushing, as shown in Figure 6. It will be seen that by means of this arrangement, hubs of one size may be securely fastened to axles of 75 various diameters.

The hub 17 is provided with sockets 24 for receiving the inner ends of bent spokes 25, these spokes being bent so that their outer ends are at ninety degrees to the inner ends. The rim 26 of the pulley 14 is 80 also provided with sockets 27 for receiving the outer ends of these spokes. This rim is preferably split and the parts held together by means of bolts 28 shown in Figure 2. This provides a universal driving connection between the rim and the axle so that the complete arrangement forms a universal wheel or pulley which is adapted to oscillate or swing freely in all directions with respect to the axle while the driving relation is 85 maintained.

On account of the rim being free to oscillate or gyrate with respect to its axis, it is necessary or desirable to provide means for holding the wheel in a substantially vertical plane, while permitting it to swing in a horizontal plane. One form of such guide is shown in Figures 6 and 7 in which a bar 29 is pivoted at 30 to a bracket 31 secured to the truck frame 11. Two wheels or rollers 32 are carried by the bar 29 and engage with the opposite sides of the rim 26. These wheels or rollers tend to hold the pulley upright while permitting it to swing in a horizontal direction as indicated by the dotted lines in Figure 7.

The generator 33 is hinged at 34 to the bottom of the car 35 and is driven by means of a universal wheel or pulley 36, which is similar in construction to the pulley 14. However, in this instance the rim 37 is not split. The hub 38 is connected to the rim by bent spokes 39 and is split in the plane of the wheel, the parts being held together by bolts 40. This hub has a bearing or tubular projection 41, which is secured to a shaft 42 of the generator by means of set screws 43 or in any other suitable manner.

A bracket 44 is secured to the generator and has a bar 45 pivoted thereto at 46. This bar is provided with guide rollers 47 to engage with the rim 37 for guiding the pulley.

A driving belt 48 passes around the pulleys 14 and 36. One or more adjustable springs 49 are arranged to pull on the generator 33 so as to keep the belt tightened at all times.

In the modification shown in Figure 9, the pulley 36 is provided with two guide rollers 50, which engage with the same side of the wheel, one being at the top and the other at the bottom. These rollers are carried by arms or bars 51, which are pivoted at 52 to brackets 53 secured to the generator. It will also be noted that a similar modification may be utilized with the pulley 14, although I prefer the arrangement above described.

With this approved form of transmission, the pulleys on the axle and generator will always stand in the same vertical plane or be in alignment with each other and with the belt. Consequently a proper driving relation is always maintained and there will be little or no chance of the belts being thrown off or lost in actual operation. It will also be noted that the device can be readily taken off of one car and applied to another, or new parts supplied which fit various sizes of axles.

It will also be noted that various changes may be made in the details of construction and arrangement of the parts in order to apply the transmission to various types of cars, and therefore I do not wish to be limited to the particular arrangement herein

shown and described, except as specified in the following claims:

1. In a car lighting system, the combination of a hub adapted to be secured to the car axle having sockets therein, a split rim having sockets formed integrally therewith, means for fastening the parts of the rim together and bent spokes engaging with the sockets in the hub and the sockets in the rim. 75

2. The combination of a pulley rim having sockets formed integrally therewith, bent spokes engaging with said sockets, a split hub for receiving the inner ends of the spokes and means for fastening the hub to a shaft of a railway car. 80

3. In a car lighting system, the combination with a car including trucks supported by wheels and axles, of a universal wheel mounted on one of the axles, a generator mounted on the car body and provided with a driving wheel, a belt passing over said wheels and guides supported by the truck frame for holding the universal wheel in a given plane. 90

4. In a car lighting system the combination of a wheel mounted for universal movement on the axle of a railway car, a bar pivotally mounted adjacent to the wheel and guide rollers carried by said bar and adapted to engage with the opposite sides of the wheel. 95

5. In a car lighting system the combination with a universal wheel mounted on the car axle, of guide rollers engaging with the opposite sides of the wheel adjacent to the top thereof, a bar on which said rollers are mounted and a pivot for said bar, said pivot being positioned in a plane passing through the longitudinal center of the wheel. 100

6. The combination with a generator for a railway car, of a universal wheel mounted on the generator shaft, means carried by the generator for guiding said wheel to hold it in normal position and a belt for turning said wheel. 110

7. The combination with a railway car having a generator mounted thereon, of a universal wheel mounted on one of the car axles, a universal wheel on the generator shaft and a belt over said wheels. 115

8. The combination with a railway car, of a generator mounted on the bottom of the car, a universal pulley secured to the generator shaft, a universal pulley secured to one of the car axles and a belt for said pulleys. 120

9. The combination with a railway car, of a universal pulley secured to one of the axles of the car, guide rollers for holding said pulley in substantially vertical position, a generator hinged to the bottom of the car, a universal pulley secured to the axle of the generator, guide rollers for holding said 125

pulley in vertical position, means carried by the truck frame of the car for supporting said guide rollers, a belt for said pulleys and a tension device coacting with the generator or holding the belt tight.

10. The combination with a railway car axle, of a pulley mounted for universal

movement on said axle, guides for said pulley, a generator, a pulley for universal movement on the generator shaft, guides for said pulley and a belt running over said pulleys.

EUGENE G. SMITH.
